TOY RAILWAY

Georg Einfalt, Nuremberg, Germany

Application April 26, 1937, Serial No. 139,028
In Germany February 26, 1937

1 Claim. (Cl. 46—216)

This invention relates to a toy-railway with automatic reversal of the direction, and with automatic switching on and off of the lamps of signal disks at every reversal.

5 I am aware of the existence of toy-railways with automatic reversal of the direction, but apart from the fact that their driving wheel-work is complicated and expensive, they lack an automatic actuation of the signal disks, where such 10 are provided, especially as concerns the appertaining lamps and the switches for the same. Counter to the existing toys of the type in question, the present improved railway-toy comprises a simplified driving wheel-work, also a 15 simplified reversing mechanism and illuminated signal disks, the lamps of which (green and red) are automatically switched on and off, or reversed respectively, in such a manner that the red light appears prior to effecting the reversal 20 of the locomotive, or the carriage respectively, indicating that the line is now blocked for a locomotive or carriage intended to be run in the same direction as the locomotive or carriage which had just arrived.

25 The invention is illustrated diagrammatically and by way of example on the accompanying drawing on which Figure 1 is a side view of the entire arrangement and combination of parts constituting my invention, Figure 2 is a plan of the members shown in Fig. 1, Figure 3 is a transverse section in the plane A—B of Fig. 2, seen in the direction from the right to the left, Figure 4 shows the right-hand portion of the wheel-work illustrated in Fig. 1, the figure being drawn to an enlarged scale relatively to Fig. 1, and Figure 5 is a transverse section in the plane C—D of Fig. 4.

30 On the drawing 1 denotes the rail, the profile of which is particularly distinctly visible in Figs. 3 and 5, and which may be straight or circularly 35 curved; near each end of the rail is an upwardly extending hook 2, or 2' respectively, which is 40 made of a piece of the material of the rail. The purpose of these hooks will be stated later on. At one end of the rail is a signal box 3 which 45 encloses an incandescent lamp 5 supplied with current from a dry battery 4 (Fig. 3). In the front surface of said box, opposite the rail, are two recesses 6 and 7 which are closed by transparent pieces of any suitable material, of which 50 pieces the lower one, pertaining to the recess 6, is green, and the other, pertaining to the upper recess, is red.

55 Between the recesses 6, 7 and the lamp 5 is a vertically guided slide 8 which rests with its lower edge upon a wire-bow bent as shown in Fig. 1.

In said slide is an aperture corresponding to one of the said recesses, said aperture being located normally (Fig. 1) behind the lower recess, so that the green color is visible. The bow 9 is oblique for part of its length is horizontally shiftable 5 and is guided by a vertical slot 10 provided in the front wall of the casing 3 below the recesses 6, 7. While the oblique portion of the bow is located in front of the casing, above the rail, its rear portion is located behind the casing 3 and is here integrally connected with a rod 11 located below the rail. The free end of this rod extends upwardly through a slot 12 of the rail and forms there a pin 13. In Fig. 1 are shown the two end positions of the bow 9 and the rod 11, the one position in 15 full lines, the other in dotted lines.

14 denotes the body of the locomotive in which are supported three running axles 15, 16 and 17, each of which is provided with running wheels 18. The axle 16 is the driving axle, as regards 20 driving the locomotive, but 19 is the driving axle proper as regards a spring-actuated wheel-work. On the axle 16 is a pinion 24 which meshes either directly with a cog-wheel 23 driven by the axle 19 by the intermediary of a cog-wheel 25 25 and a pinion 21, or with an intermediate pinion 26 depending on the position of the pinion 24. The axle 16 bearing this pinion is at its ends supported in slightly curved slots 25, shown in dotted lines in Fig. 4, and it depends on the position of said axle in these slots, viz. at the one or the other end of the same, whether the pinion 24 meshes directly with the cog-wheel 23 or indirectly by the intermediary of the pinion 26. 30 The ends of the axle 16 extend into a bow 27 which is located transversely with respect to the locomotive frame 14 and can be shifted in the longitudinal direction thereof as much as permitted by the slots 25. Correspondingly therewith the axle 16 can be shifted into the one and the other of the two positions in which the pinion 24 meshes either with the pinion 26 or with the cog-wheel 23, as described. The two bows are firmly connected with one another at their lower portions so as to form downwardly extending hooks 28 having each a recess 29 (Figs. 4 and 5). The hooks 28 engage alternately the rail hooks 2, 2' and the pin 13 passes then through the recesses 29 so that it is not engaged by the same.

Counter to the casing 3, at the other end of the rail 1, is a casing 31 designed as a locomotive shed or a railway terminus or the like and being large enough to receive the locomotive 14, as shown in dotted lines.

According as whether the pinion 24 of the

wheel-work of the locomotive meshes with the pinion 26 (as in Fig. 4) or with the cog-wheel 23, the locomotive will be driven in the one or in the other direction, as has already been described. When the members 23, 24, 26, 27 are in the position shown in Fig. 4, the locomotive will run into the casing 31, where the angular foot 28 of the bow 27 engages the hook 2 (see Fig. 4). The locomotive is now stopped, but there has arisen, of course, a certain inertia in the locomotive while it had been in motion, that inertia being partly due also to the acceleration arising during the running, and this being so, the axle 16 with the pinion 24 thereon proceeds in its motion, viz. in the slots 25 of the bow 27, so that it moves along in these slots until it arrives at the other end of the same where it is stopped. Owing hereto, the pinion 24 leaves the cog-wheel 23 and meshes with the pinion 26 whereupon the direction of motion of the locomotive will be reversed and the locomotive will leave the shed or terminus 31 and run now in the direction to the signal casing 3.

At that end of the wheel-work frame 14 which is located opposite the signal casing is a plate-spring 30 (Fig. 1) which projects beyond the lower edge of the respective wall of said frame and encounters the pin 13 of the rod 11 whereby this rod will be shifted, as will also the bow 9. These members (13, 11, 9) will be shifted from the position shown in Fig. 1 in full lines into the position shown in dotted lines. Therefore, the oblique portion of the bow 9 will pass away below the slide 8 which will drop and uncover the red light, but cover the green one. As the plate spring 30 gives way after the rod 11 has been shifted and comes then to a standstill, the locomotive proceeds further on its way and encounters finally the hook 2 where now the same action takes place as with the hook 2', that is to say, the axle 16 with the pinion 24 will again change its position in the slots 25 of the bow 27 and the direction of running of the locomotive

will again be reversed. The spring 30 now engages again the pin 13, the rod 11 is again shifted, the bow 9 is likewise again shifted, and the slide 8 is thereby lifted so that now the green light will be uncovered and the red one will be covered.

I wish it to be understood that I do not limit myself to all details of the constructional form of the rail and of the locomotive, as well as of the signal plant, illustrated in the drawing merely by way of example. Thus, for instance, the locomotive may have any desired outer appearance, as now being built, and may have only two running axles instead of three. It is also possible to provide a signal-plant at each end of the rail, and modifications are possible in the means for operating that plant or those plants by means of the running locomotive. The chief characteristic features of the invention reside in the arrangement and combination of parts effecting the automatic reversal of the direction of running of the locomotive or its equivalent.

I claim:

In a toy railway, in combination with a track and a vehicle movable thereon, a reversible gear-train in said vehicle, a member extending from the reversing mechanism of said gear-train down between the rails, and an optical signalling device at an end of the track, two projections extending upwardly between the rails and being spaced in the direction thereof and located near said signalling device, the projection located nearest thereto being stationary and so arranged relatively to said downwardly extending member of the reversing mechanism as to be adapted to engage it so as to operate thereby this mechanism, and the other projection being shiftable in the direction of the track and adapted to be engaged by the vehicle, and means for transmitting the movement of this projection to the said signalling device.

GEORG EINFALT.
